Primary Examiner — T. Chase Nelson*Assistant Examiner* — Ania K Dworzecka(57) **CLAIM**

The ornamental design for faucet for drinking fountain, as shown and described.

DESCRIPTION

FIG. 1 is a perspective view of faucet for drinking fountain showing my new design;

FIG. 2 is a front elevational view thereof; the rear elevation view is a mirror image thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

In the drawings, the broken lines shown in FIGS. 3 and 7 depict unclaimed subject matter only and form no part of the claimed design.
